CLAIM

The ornamental design for a display screen or portion thereof with graphical user interface, as shown and described.

DESCRIPTION

The sole FIGURE is a front view of a display screen or portion thereof with graphical user interface showing our new design.

The broken line showing of a display screen or portion thereof with graphical user interface is included for the purpose of illustrating portions of the article and forms no part of the claimed design. The greyscale shading represents a contrast in appearance. White space forms no part of the claimed design.

1 Claim, 1 Drawing Sheet
